RECOIL CHECK FOR CARBON DIOXIDE
CYLINDERS

Frank B. Allen and Scott E. Allen, Glen Ridge,
N. J., assignors to C-O-Two Fire Equipment
Company, Newark, N. J., a corporation of
Delaware

Application November 19, 1935, Serial No. 50,614

8 Claims. (Cl. 169—11)

The present invention relates to an improved method of and means for checking the recoil of a container holding highly compressed fluid, such, for instance, as liquefied carbon dioxide.

5 War vessels are commonly furnished with portable cylinders of liquefied carbon dioxide for use in extinguishing fires. The cylinders are usually mounted at some convenient location on a side wall or a bulkhead and the mounting is such that in an emergency the cylinders may be quickly dismounted and put into service. However, in combat there is always the danger that a cylinder may be punctured by a shot or a fragment of a shell and the sudden release of the highly compressed fluid will result in a powerful recoil that will tear the cylinder from its mounting and hurl it forth at high velocity. If the shot punctures only one side of the cylinder the recoil will result from unbalanced discharge through the puncture, but even should the shot pass clear through the cylinder, making openings in diametrically opposite points, a powerful propelling force will nevertheless be produced as a result of the difference in area of the opposed orifices.

15 Experiments have shown that when a shot is fired through a cylinder the orifice at the entrance side is smaller than that at the exit side. The pressure of the liquefied carbon dioxide in the cylinder will be under average conditions over 800 pounds per square inch, and in numerous tests cylinders punctured by projectiles have been torn from their mountings and hurled a distance of over 200 feet in the direction from which the shot came. Obviously, a heavy cylinder propelled with such force would wreak havoc in confined quarters, particularly since the cylinder would be continuously propelled like a rocket, until all of its liquid carbon dioxide content was exhausted.

25 An object of the present invention is to provide a method of and means for anchoring or tethering a cylinder in such a way that the full force of the recoil will not be abruptly and directly opposed, and the strain on the tether will be kept within safe limits.

30 Another object is to provide a recoil check or tether which may be instantly released, when desired, to permit of removing the cylinder from its mounting for use or test.

35 A further object of the invention is to provide a tether attached at one end to the neck of the cylinder, and anchored at the other end to a bulkhead or supporting wall. An advantage of such point of attachment is that it is less likely to be hit because of the smaller exposed area.

40 Another and most important advantage of making the tether fast at the neck is that in case the body of the cylinder is punctured the tether will not be subjected to the direct force of the recoil, and the cylinder instead of being stopped abruptly will be tripped and diverted from its

direction of flight. The resultant comparatively gradual stopping of the cylinder relieves the tether of sudden excessive strains that might rupture the tether.

Other objects and advantages of our invention will appear in the following description of a preferred embodiment and thereafter the novelty and scope of the invention will be pointed out in the claims.

In the accompanying drawing:

Figure 1 is a view in front elevation of a portable cylinder suitably mounted and also provided with our improved recoil check;

Fig. 2 is a view in side elevation of the same;

Fig. 3 is a view in section taken on the line 3—3 of Fig. 1; and

Fig. 4 is a section taken on the line 4—4 of Fig. 1 showing particularly a readily releasable attachment means between the tether and the cylinder.

In the drawing, a cylinder 10 containing liquefied carbon dioxide or other highly compressed fluid is provided with a discharge head 11 screwed upon the neck 12 of the cylinder. The discharge head may be of any suitable type, such, for example, as that shown in Patent No. 1,974,254, issued September 18, 1934. The discharge head has a hand wheel 14 operable to puncture the usual sealing disk and release fluid from the cylinder into a flexible conduit 15 which terminates in a discharge horn 16. This horn is normally held against the side of the cylinder by a spring clip 17 secured to the cylinder.

As shown in Fig. 2 the cylinder is normally supported against a bulkhead 18 in such a manner that it may be readily withdrawn from the bulkhead when desired. The mounting comprises a vertical plate 19 secured to the bulkhead and provided at its upper end with a wall hook 20 which engages an apertured lug 21 projecting from the discharge head 11. At the lower end of the plate 19 there is a spring clip 22 which partially encircles the body of the cylinder 10.

Fitted tightly upon the neck 12 of the cylinder is a collar 24 which has an apertured lug 25 adapted to fit between the arms of a clevis 26. These arms are also apertured and a swivel connection between the clevis and the lug 25 is provided by inserting a pin 27 through the aligned apertures. The clevis is secured to one end of a cable 28. This cable is preferably made of stainless steel, so that it will have great strength and will be proof against corrosion. The opposite end of the cable terminates in a bolt 29 threaded through an aperture in the bulkhead 18. A nut 30 screwed upon the projecting end of the bolt serves to lock the bolt and hence the cable firmly to the bulkhead.

The pin 27 is provided at its upper end with an eye 32 which may be connected by a chain

33 to the clevis. A spring catch is provided to hold the pin in engaging position without, however, preventing the pin from being readily removed to permit of disconnecting the clevis from the lug 25. This spring catch is illustrated in detail in Fig. 4. The pin is transversely bored to receive a ball 34. The bore is reduced slightly at one end so as to retain the ball and yet permit it to project slightly from the surface of the pin.

10 A spring 35 presses the ball outwardly and the spring is backed by a plug 36 threaded in the transverse bore.

The cylinder is readily mounted on the wall or bulkhead 18 by hooking the lug 21 over the wall hook 20 and slipping the body of the cylinder into the spring clip 22. Then the tether is made fast by inserting the pin 27 through the aligned apertures in the clevis and the lug 25. The ball 34 is depressed as the pin is inserted and then springs out to prevent the pin from being accidentally displaced. However, the ball does not project far enough to prevent intentional withdrawal of the pin. Hence in case of a fire the pin may be instantly withdrawn and the cylinder lifted off its hook. Should the cylinder be pierced by a projectile while it is mounted and tethered in place the recoil caused by the escaping fluid may tear the cylinder from its mounting, but the cylinder will be checked by the tether 25
